Primary Examiner — Karen S Acker*Assistant Examiner* — Elizabeth S Ko(74) *Attorney, Agent, or Firm* — Reinhart Boerner Van Deuren P.C.(57) **CLAIM**

I claim the ornamental design for a saw guide, as shown and described.

DESCRIPTION

FIG. 1 is a perspective view of a saw guide;

FIG. 2 is a perspective view thereof;

FIG. 3 is a back view thereof;

FIG. 4 is a front view thereof;

FIG. 5 is a side view thereof;

FIG. 6 is a side view thereof showing the side opposite that shown in FIG. 5;

FIG. 7 is a top view thereof; and,

FIG. 8 is a bottom view thereof.

The broken lines in the drawings depict portions of the saw guide that form no part of the claimed design.

1 Claim, 6 Drawing Sheets(56)
